UNITED STATES PATENT OFFICE

ROBERT F. PARKS, OF COMPTON, CALIFORNIA

ELEVATING AND ROTATING DEVICE

Application filed June 23, 1930. Serial No. 463,161.

This invention relates to an elevating and rotating device, by means of which one stand of pipe is unscrewed from another. This device is particularly advantageous around 5 an oil well during either the drilling or producing operations.

The prime object of my invention is to provide a novel elevating and rotating device which attaches to the top of the stand of pipe 10 to be unscrewed, and is actuated by the upward movement of the blocks which support the device.

Another object is to provide a novel elevating and rotating device of the character 15 stated which operates through a gear means between the blocks and the elevator encircling the pipe, thereby rotating the pipe to screw or unscrew the same.

Still another object is to provide a device 20 of the character stated which is attached to the elevating blocks, and which will also serve to support the pipe while it is being removed from the point where it was unscrewed from the lower stand.

Other objects, advantages, and features of 25 invention, may appear from the accompanying drawings, the subjoined detailed description, and the appended claims.

In the drawings

Figure 1 is a side elevation of my elevating and rotating device in operative position.

Figure 2 is an enlarged side elevation, with parts in section, of my device.

Figure 3 is a longitudinal, sectional view 35 of the rotating screw, and the rotating means co-operating therewith.

Figure 4 is a bottom plan view of the weight.

Figure 5 is a top plan view of the bridge, 40 and of the rotating screw.

Referring more particularly to the drawings, the numeral 1 indicates the rotary table in which the lower stand of pipe 2 is secured. The stand of pipe 3 rises above the rotary 45 table and is secured to the stand 2 by a threaded joint. After this joint has been loosened by the tongs, or the like, my device becomes operative to unscrew the joint and remove the stand 3.

My elevating and rotating device 4 com-

prises a bail 5 which is secured to a block 6. The block 6 is positioned at the bottom of the bail 5 and the purpose thereof will be further described. The travelling blocks 7 are attached to the bail 5 by means of an eye 8 55 which depends from the blocks.

A bridge 9 is secured between the bail 5 adjacent the upper end thereof. In this bridge I journal a pair of sheaves 10—11. The purpose of these sheaves will be further 60 described. An actuating shaft 12 depends from the bridge 9 and is non-rotatably held in the bridge by some suitable means, although under strain, it is desirable that the shaft shall rotate in order not to break any of 65 the co-acting parts. To accomplish this purpose, I provide a drum 13 on the top of the shaft 12, and this drum is engaged by a pair of brake shoes 14—14. The brake shoes grip the drum tightly so that the drum and the 70 shaft can only rotate when a very high torque is exerted upon the shaft. The brake shoes 14—14 are pressed together by suitable springs 15—15 and 16—16. The shaft 12 is 75 cut with a double thread as shown at 17, and these threads are engaged by members so as to rotate the pipe stand 3, as will be subsequently described.

The shaft 12 extends into a sleeve 18 and moves up and down in the sleeve during the 80 operation of the device. To the lower end of the sleeve 18 there is pivotally secured a yoke 19 and a pair of links 20—20 fit over the yoke 19. The lower ends of the links 20—20 are attached to an elevator 21, which elevator 85 engages and grips the upper end of the pipe stand 3. The elevator 21 may be of any usual and well known design, and the detailed construction thereof forms no part of 90 this invention.

A pipe section 22 is suitably attached to the upper end of the sleeve 18, and this pipe section extends upwardly around the shaft 12. To the inside of the pipe section 22 I secure a pair of superposed female clutch members 23—24. Co-operating with the clutch member 23, is a male clutch member 25, and similarly a male member 26 co-operates with the clutch 24. The clutch members 25—26 95 are each provided with grooves which engage 100

the left and right hand threads respectively, of the shaft 12. Thus the member 25 will constantly rotate in a right hand direction while the clutch member 26 will rotate in a 5 left hand direction. Whichever member of the pair 25—26 engages its corresponding female clutch member, that is the direction in which the pipe section 22 and the sleeve 18 will rotate.

10 It is evident that one of the members 25 or 26 must be held out of engagement at all times. That is, only one must engage its corresponding female clutch member. To accomplish this, I surround the pipe section 22 with a rotatable ring 27. This ring is provided with upward and downward extending cam slots 28—29 respectively. A pair of clutch releasing fingers 30—31 are positioned 15 in the pipe section 22, and surround the shaft 12. These releasing fingers have outwardly extending pins 32—33 respectively which enter the cam slots 28—29 respectively. Thus as the ring 27 is rotated, one of the clutch 20 engaging fingers 30 or 31 is moved into engagement with the corresponding male clutch member 25 or 26 to hold said male member out of operative engagement, as 25 shown in Figure 3. The other member will be free to engage its female clutch member, and thus rotate the pipe section, sleeve and 30 attached parts either to the left or to the right. By the above arrangement, it is impossible to have both of the clutches simultaneously operable.

35 The sleeve 18 is guided through the blocks 6 and a ball bearing 34 is mounted in the top of said block, and the bottom of the pipe section 22 engages the ball bearing in the lowered position of said section, and thus minimizes 40 the frictional resistance between the block and the pipe section.

To return the sleeve 18, pipe section 22 and attached parts to their raised position, I provide a counter weight 35 which is slidably 45 mounted on the bail 5, and the counter weight surrounds the sleeve 18. A pair of chains, cables, or the like, 36—37 are secured to the weight 35, pass over the sheaves 10—11 respectively, and then extend downwardly and 50 are attached to the races of a ball bearing 38. The ball bearing 38 is mounted in a fitting 39 which is secured to the top of the pipe section 22.

If it is desired to use the device merely as 55 an elevator, I latch the counter weight 35 in its raised position by some suitable means, which means may be a plate 40 which is rotatably mounted on the bottom of the weight 35. A pair of dogs 41—42 are pivotally 60 mounted in the weight 35, and the lower depending tips thereof enter cam slots 43—44 respectively, in the plate 40. Thus, when the plate 40 is rotated either to the left or to the right, the dogs 42 will be retracted and cannot 65 engage recesses 45—46 in the bail.

The operation of my invention is as follows: The blocks 7 are lowered until the elevator 21 can engage the upper end of the pipe stand 3. The clutches 25 or 26 have been previously arranged so that the rotation of 70 the sleeve 18 will be counter clockwise. Now, by pulling upwardly on the block 7, the bail 5, bridge 9 and shaft 12 will also be pulled upwardly relative to the sleeve 18, pipe section 22, and the clutches therein. This relative movement of the clutch and the threads in the pipe will cause the engaging clutch to rotate and also carry with it the pipe section, sleeve, the links 20 and the elevator 21. Since the elevator tightly grips the top of 80 the pipe stand 3, it will unscrew the same from the stand 2.

The block 7, bail 5 and attached parts are held against rotation because of the spaced cables which encircle the sheaves in the travelling block. As soon as the pipe stand 3 has been unscrewed, the operator can continue to raise the pipe the required amount and move it to one side of the derrick, or any place desired. When the pipe stand 3 has been removed to its desired place of storage, the counter weight 35 is latched in its raised position until the next stand has been engaged. Then it is released and will drop into its lowermost position as shown in Figures 1 and 90 2, and the device is ready for the next operation.

The counter weight 35 is slightly heavier than the combined weights of the elevator, 100 links, yoke, sleeve 18, pipe section 22 and the clutch assemblies. The reason for this is that the counter weight must raise all of these in order to prepare the device for its next rotating operation. The threads 17 on the shaft 12 are of sufficient length so that the proper number of turns is imparted to the elevator 21 in order to unscrew the pipe stand 3.

A stout coil spring 47 is set in a recess in the block 6 and this spring bears against the ball bearing 34. The purpose of this spring is to relieve the shock when the elevator 21 engages the collar on the top of the pipe stand 3 when this pipe stand is being elevated.

Having described my invention, I claim:

1. An elevating and rotating device for pipe comprising travelling blocks, a bail suspended from the travelling blocks, a threaded shaft mounted in the bail, a sleeve extending over the shaft, means on the sleeve engageable with the threads of the shaft whereby 110 said sleeve is rotated as the blocks are raised, an elevator and links attached to the elevator and to said sleeve, and counter weight means attached to said sleeve whereby said sleeve is drawn upwardly over the shaft when the pipe 120 is disengaged from the elevator.

2. An elevating and rotating device for pipe comprising travelling blocks, a bail suspended from the blocks, a threaded shaft mounted in the bail, a sleeve extending over 130

the shaft, an elevator adapted to engage the pipe, means attaching the elevator to the sleeve, clutch means in the sleeve, said clutch means being adapted to engage the threads 5 of the shaft whereby the sleeve is rotated as the shaft is raised.

3. An elevating and rotating device for pipe comprising travelling blocks, a bail suspended from the travelling blocks, a bridge 10 secured to the bail, a threaded shaft suspended from the bridge, a sleeve extending over the shaft, a pair of clutches in the sleeve, said shaft being formed with right and left hand threads, one of said clutches engaging 15 the right hand threads and the other the left hand threads, disengaging means for the clutches, an elevator, and means suspending said elevator from the sleeve.

4. An elevating and rotating device for 20 pipe comprising travelling blocks, a bail suspended from the travelling blocks, a bridge secured to the bail, a threaded shaft suspended from the bridge, a sleeve extending over the shaft, a pair of clutches in the sleeve, 25 said shaft being formed with right and left hand threads, one of said clutches engaging the right hand threads and the other the left hand threads, disengaging means for the clutches, an elevator, and means suspending 30 said elevator from the sleeve, and counter weight means attached to the sleeve whereby said sleeve is raised when there is no work in the elevator.

5. An elevating and rotating device for 35 pipe comprising travelling blocks, a bail suspended from the blocks, a bridge in the bail, a threaded shaft suspended from the bridge, a sleeve extending over the shaft, said shaft being formed with right and left hand 40 threads, a pair of clutches in the sleeve, one of said clutches engaging the right hand, and the other the left hand threads, means engaging said clutches whereby either may be held inoperative, an elevator adapted to grip 45 the pipe, and links attached to the elevator and to said sleeve.

6. An elevating and rotating device for 50 pipe comprising travelling blocks, a bail suspended from the blocks, a bridge in the bail, a threaded shaft suspended from the bridge, a sleeve extending over the shaft, said shaft being formed with right and left hand 55 threads, a pair of clutches in the sleeve, one of said clutches engaging the right hand, and the other the left hand threads, means engaging said clutches whereby either may be held inoperative, an elevator adapted to grip the pipe, and links attached to the elevator and to said sleeve, a counter weight, means 60 attaching said counter weight to the sleeve, said counter weight being adapted to pull the sleeve upwardly when there is no work in the elevator.

7. An elevating and rotating device for 65 pipe comprising travelling blocks, a bail sus-

pended from the blocks, a bridge on the bail, a threaded shaft suspended from the bridge, brake means gripping said shaft, a sleeve extending over the shaft, said shaft being formed with right and left hand threads, a pair of clutches in the sleeve, one of said clutches engaging the right hand, and the other the left hand threads, means whereby one of said clutches is held inoperative while the other is active, an elevator, and means 70 attaching said elevator to the sleeve.

8. An elevating and rotating device for pipe comprising travelling blocks, a bail suspended from the blocks, a bridge on the bail, a threaded shaft suspended from the bridge, brake means gripping said shaft, a sleeve extending over the shaft, said shaft being formed with right and left hand threads, a pair of clutches in the sleeve, one of said clutches engaging the right hand, and the other the left hand threads, means whereby one of said clutches is held inoperative while the other is active, an elevator, and means 75 attaching said elevator to the sleeve.
